Introduction to Electron Microscopy by S. Wischnitzer, Pergamon Press, New York, 1962, pages

[57] **ABSTRACT**
A specimen which is to be analyzed is initially introduced to an electron microscope housing at a location along the electron beam path between the objective lens and subsequent projection lenses in order to provide a smaller magnification relative to the magnification provided with the specimen in the normal object plane of the objective lens, but which provides greater mechanical facility in effecting the entry and removal of the specimen from the housing. While entry at this location results in less magnification of the specimen and image resolution, it is nonetheless suitable for a survey of the specimen in order to determine the adequacy of the specimen for analysis at the object plane.

SPECIMEN ANALYSIS IN AN ELECTRON MICROSCOPE

This invention relates to electron microscopes. The invention relates more particularly to a method and means for facilitating specimen analysis with an electron microscope.

A specimen is examined in an electron microscope by directing a beam of electrons at the specimen and viewing an enlarged image of the specimen resulting from the electron impingement and electronic magnification. In a transmission type of electron microscope, for example, the electrons which impinge upon the specimen are partly scattered and partly transmitted through the specimen. The transmitted electrons are controlled by a number of electromagnetic lenses and subsequently projected on a fluorescent screen thereby forming a greatly enlarged image of a portion of the specimen for detailed viewing. The impinging electron beam is formed by means comprising a source of electrons and an electromagnetic condensing lens system while those electrons transmitted through the sample are focused and projected at the fluorescent screen by objective, intermediate, and projection electromagnetic lenses. These lens systems along with the beam source, the fluorescent screen and the specimen are mounted in an evacuated environment of a housing for the microscope.

A specimen which is to be analyzed with an electron microscope is prepared, deposited in a receptacle, and positioned at an object plane of the lens system. The object plane is generally located near a gap existing in the electromagnetic objective lens. The specimen receptacle, which is introduced to the housing through an airlock arrangement, must be carefully manipulated in order to position the specimen at the gap of the objective lens. It frequently occurs that after preparation of the specimen, entry of the receptacle through the airlock, and careful manipulation of the receptacle for positioning the specimen in the objective plane, the specimen is found upon initial examination to be unsuitable for an analytical determination. The specimen may be unsuitable because of improper preparation, dehydration in the evacuated environment or other degradation, and the specimen must then be removed and replaced. This of course is undesirable since it is unproductive and time consuming.

Accordingly, it is an object of this invention to provide a method and means for enhancing the analysis of a specimen in an electron microscope.

Another object of the invention is to provide a method and means for establishing the suitability of a specimen for analysis in an electron microscope.

In accordance with the general features of this invention, a specimen which is to be analyzed is initially introduced to an electron microscope housing at a location along the electron beam path between the objective lens and subsequent projection lens system for providing a smaller magnification relative to the magnification provided at the objective plane, but which provides greater mechanical facility in effecting the entry and removal of the specimen from the housing. While entry at this location results in less magnification of the specimen and inferior image resolution, it is nonetheless suitable for a survey of the specimen in order to determine the adequacy of the specimen for analysis at the object plane. The adequacy of a

specimen for more detailed analysis is noted and the specimen is then removed for this location and introduced to the microscope at the object plane of the objective lens. The operator is thus assured that the sample, which is now positioned for detailed analysis, is suitable for detailed analysis.

An apparatus providing the general features of this invention includes means for positioning a specimen receptacle at a location along the axial path of the electron beam at a point between the fluorescent screen or other projection plane and the objective plane of the objective lens. In a particular arrangement, transport means are provided for simultaneously introducing a plurality of specimens into the microscope housing at this location, for sequentially surveying all of the specimens and for simultaneously removing the survey specimens from the housing.

These and other objects and features of the invention will become apparent with reference to the following specifications and to the drawings wherein:

FIG. 1 is a cross sectional view of an electron microscope constructed and operated in accordance with the features of the invention.

FIG. 2 is an elevation view, partly in section, of an embodiment of a specimen survey transport means fabricated in accordance with the invention; and

FIG. 3 is a plan view of the transport of FIG. 2. Referring now to FIG. 1, an electron microscope is shown to include a cylindrical housing 10 within which a relatively high vacuum is established. A vacuum is established in the upper sections of the microscope by a pumping system 12 which is coupled to the housing through a conduit 14 while the lower stages are evacuated through a conduit 18. A beam of electrons 20 is derived from a well-known source of electrons, which for simplification in the drawings is represented by a rectangle 22 in FIG. 1. The electrons provided by this are accelerated centrally along the length of the cylindrical housing 10 toward a fluorescent screen 24. The microscope of FIG. 1 is illustrated to be of the transmission type wherein the electrons of beam 20 impinge upon and are partially transmitted through a sample 25 which is located in a receptacle 26. Those impinging electrons which penetrate the sample are accelerated toward the fluorescent screen 24 by a high voltage, not illustrated, where they excite the screen phosphors and provide a magnified image of the sample.

An electron optical system is provided in order to collimate the beam 20 of electrons which impact the specimen and in order to focus and project at the screen 24 those electrons which are transmitted through the specimen. The electrons from source 22 are collimated into the beam 20 by a first electromagnetic condensing lens comprising a core 30 of ferromagnetic material and an electrical winding 32 positioned within the core 30 and having a plurality of turns. An electromagnetic field established by this lens is proportional to a current flowing in the winding 32. Circuit means, not illustrated, are provided for varying the current in this winding as well as the current in windings of other electromagnetic lenses, referred to hereinafter. A second electromagnetic condensing lens 34 is provided and is constructed in a manner similar to the first lens. These lenses are supported in the cylindrical housing 10 on plates 36 and 38 which are mounted

to an inner wall of the cylindrical housing 10. Each of these plates includes a centrally located aperture through which the electron beam is transmitted.

Focusing and projection of the transmitted electrons of electron beam 20 is accomplished by an electromagnetic objective lens 40, an intermediate lens 42, and a projection lens 44. The objective lens 40 is mounted between plates 46 and 48 and extends between the inner walls of the housing 10. The plate 46 includes a centrally located aperture while the plate 48 includes a slot extending diametrically therethrough for positioning an aperture stop and, in accordance with the features of this invention, a specimen survey rod, discussed hereinafter. A ferromagnetic core 49 of the objective lens 40 includes a gap near an upper section thereof as viewed in FIG. 1. The object plane of the lens is located in the area of this gap. The specimen receptacle 26 which is positioned on the plate 46 extends through the aperture in the plate 46 and locates the specimen 25 in the gap. For purposes of illustration in FIG. 1, the sample receptacle 26 is shown vertically displaced above the object plane location. In operation, the receptacle 26 is lowered through the aperture in the plate 46 and a shoulder of this receptacle will support the receptacle suspended from the plate 46 with the specimen 25 located in the gap at the object plane.

An aperture stop, not illustrated, is in practice and during detailed analysis of a specimen located at an intermediate focal point between the objective lens 40 and the intermediate lens 42 for providing an electron beam of desired diameter. The intermediate lens 42 is positioned between a support plate 48 and a support plate 50. The latter mounting plate includes an aperture centrally located therein for passage of the electron beam therethrough. The electromagnetic projection lens 44, which is generally similar in construction to the objective and intermediate lenses and which includes a core of ferromagnetic material and a winding positioned therein, is suspended from the plate 50.

An air lock for introducing a specimen to the evacuated environment and for removing the specimen without significantly interrupting the evacuation atmosphere is represented by the rectangle 52. The air lock 52 includes an intermediate chamber operating at an intermediate pressure through which the specimen receptacle passes when introducing the sample into the instrument. The further details of an air lock are well known and for convenience in the presentation are not shown. A mechanical means, illustrated as the manipulating tongs 54, is provided for locating the specimen receptacle 26 centrally within the microscope housing 10, for lowering the receptacle into the gap of the objective lens 40, and for removing the same when desired. An air lock 56 along with a means comprising tongs 58 is provided for positioning an aperture stop at the location between the objective and intermediate lenses. As discussed hereinafter, the tongs 58 are also employed for manipulating a sample holder at this location.

In operation, a sample is positioned in the receptacle 26 and is introduced into the specimen stage of the microscope through the air lock 52. The specimen receptacle 26 locates the specimen in the gap of the objective lens at or near the object plane. An aperture stop of desired diameter, not illustrated, is introduced

through air lock 56 and is located within the housing between the objective and intermediate lenses at the image plane of the objective lens. The lenses 30 and 34 function to collimate the electron beam 20 and the

electrons of the collimated beam 20 which impinge upon the specimen at the image plane of the objective lens will extend through the aperture stop and will be focused by the intermediate lens 42. The electron beam is then projected at the fluorescent screen 24 by the projector lens 44 causing a greatly magnified image of the sample to be produced at this screen. The magnified image can be viewed by an operator of the instrument through a transparent window 60 located in the housing wall.

As indicated hereinbefore, the introduction of a sample through the air lock into the housing and the manipulation of the specimen holder 26 into the object plane can be relatively time consuming. The subsequent discovery that the specimen is defective or im-

properly prepared or has suffered some degradation generally renders attempts at detailed analysis ineffective. The steps involved in introducing the specimen into the instrument have therefore been not only time consuming but inefficient. In accordance with the features of this invention, one or more specimens are sur-

veyed at a location along the electron beam path between the object plane and the fluorescent screen 24. A survey as used in these specifications and claims refers to viewing a specimen generally in order to ascertain its characteristic of suitability for further detailed analysis.

Although the magnification factor and image resolution at a location alternate to the object plane of the objective lenses will be substantially less than that provided at the object plane, nonetheless the magnification is sufficient for surveying the prepared sample in order to establish the worthiness for detailed examination at the object plane of the object lens. In the illustration of FIG. 1, the aperture stop is removed and a survey transport arrangement is located at the image plane of the objective lens. A plurality of specimens are positioned on a transport body 70 which is readily located in the instrument. The specimens are sequentially positioned in the beam path in order to project their image at the screen 24.

FIG. 2 is an enlarged view, partly in section of the transport body 70 for use with the sample survey technique of this invention. The body 70 comprises a rod which has formed therein a plurality of longitudinally located apertures 72. These apertures are conically shaped. A specimen 76 is deposited on a lower surface 77 of this pan, the surface 77 of the pan comprising an electron permeable material. A plurality of specimen pans are positioned on the rod 70. The apertures 72 are located equidistantly apart and an associated cove or depression 78 is provided for each of the apertures 72. The coves 78 comprise a seat for a ball 80 which engages the cove and functions as a detent mechanism. The rod 70 extends through a guide groove 79 formed in the support plate 48 of the microscope. A vertically extending screw 82 is adjustable for establishing a desired compression of a spring 84. The spring 84 provides a resilient force against which the ball 80 acts when the rod is pushed or forced in a longitudinal direction. The rod 70 is advanced by a force exacted thereon through extension rod 86. Each

of the coves 78 is located with respect to an associated aperture 72 for establishing the positioning of a specimen of the associated aperture in the electron beam path when the cove is detented and locked by the ball 80.

Each of the specimens located in the pans 74 are surveyed at the lower magnification in order to establish their suitability for further detailed examination in the specimen stage. The survey of a plurality of the specimens is accomplished without removing other specimens from the instrument while subsequent ones are being surveyed. Upon completion of the survey of all of the specimens at this survey station, the specimens are removed through the air lock 56, the aperture stop is replaced, and those specimens found to be suitable for further examination can be individually introduced to the specimen stage through air lock 52.

Thus a method and apparatus have been described which enhance the operation of an electron microscope by assuring the operator of the instrument that the specimen to be examined at the specimen stage is properly prepared and suitable for analysis. The loss of time as experienced with prior apparatus during the entry and removal of an unsuitable specimen at the object plane is therefore avoided and efficiency of analysis is greatly enhanced.

While the arrangement of FIG. 1 illustrates the survey station located in the electron beam path at the image plane of the objective lens, the survey station may equally well be located at the object plane of any

lens in the microscope projection system.

While I have illustrated and described a particular embodiment of my invention, it will be understood that various modifications may be made therein without departing from the spirit of the invention and the scope of the appended claims.

What is claimed is:

1. A method of electron microscope specimen analysis in an electron microscope including electromagnetic collimating, objective, intermediate, and projection lenses comprising the steps of:

generating an electron beam;

accelerating said electron beam along a preestablished path for impingement and penetration of a material positioned in said path;

positioning a material to be analyzed in said electron beam path at a survey location positioned intermediate said objective lens and said intermediate lens,

projecting the electrons which penetrate the material toward an electron responsive means for providing a magnified image of said material; and,

withdrawing said material from said survey location and positioning said material at a specimen location intermediate said collimating lens and said objective lens for detailed analysis of said material for providing a significantly greater magnified image of said material at said electron responsive means.
